[57] CLAIM

The ornamental design for a wall mounted dual dryer system, as shown and described.

DESCRIPTION

FIG. 1 is a perspective view of a wall mounted dual dryer system showing my new design.

FIG. 2 is a top plan view thereof.

FIG. 3 is a left side elevation view thereof.

FIG. 4 is a right side elevation view thereof.

FIG. 5 is a rear elevation view thereof.

FIG. 6 is a bottom plan view thereof.

FIG. 7 is a front elevational view thereof.

FIG. 8 is a right side elevational view thereof.

FIG. I

FIG. 6

FIG. 7

FIG. 8

UNITED STATES PATENT AND TRADEMARK OFFICE
CERTIFICATE OF CORRECTION

PATENT NO. : Des 301,638

Page 1 of 2

DATED : July 13, 1989

INVENTOR(S) : Kevin S. Russell

It is certified that error appears in the above-identified patent and that said Letters Patent is hereby corrected as shown below:

The sheet of Drawing consisting of Figures 2-5 should be added
as per attached sheet.

Signed and Sealed this
Fourth Day of December, 1990

Attest:

HARRY F. MANBECK, JR.

Attesting Officer

Commissioner of Patents and Trademarks
